UNITED STATES PATENT OFFICE.

HENRY R. TOWNE, OF NEW YORK, N. Y., ASSIGNOR TO THE YALE & TOWNE MANUFACTURING COMPANY, OF STAMFORD, CONNECTICUT.

DESIGN FOR A PADLOCK-CASE.

SPECIFICATION forming part of Design No. 32,921, dated July 10, 1900.

Application filed June 4, 1900. Serial No. 19,076. Term of patent 7 years.

To all whom it may concern:

Be it known that I, HENRY R. TOWNE, of New York city, New York county, State of New York, have invented and produced a new and original Design for a Padlock-Case, of which the following is a full, clear, and exact description, reference being had to the accompanying drawing, forming a part thereof.

The accompanying drawing is a view in elevation, illustrating my design.

The leading feature of my design consists of a padlock having the representation of crossed cannon thereon.

A represents the body of the padlock, and B the bow at the upper end thereof. The general shape of the body A is approximately that of a shield, and disposed diagonally across

said shield are the representations of cannon 1, crossing each other and tied together by a rope or cable 3, passing through a block 2, represented between the upper ends of the cannon 1. The representation of a short rope 4 is located above the block, and a loosely-knotTED rope 5 is shown below the lower ends of the cannon, and cartridges 6 are represented on each side of the crossed cannon.

What I claim is—

The design for a padlock-case herein shown and described.

HENRY R. TOWNE.
